UNITED STATES PATENT OFFICE.

HERMAN BACHARACH, OF PITTSBURGH, PENNSYLVANIA, ASSIGNOR TO BACHARACH INDUSTRIAL INSTRUMENT COMPANY, A CORPORATION OF PENNSYLVANIA.

PROTECTING HOOD OR CASING.

Application filed January 31, 1921. Serial No. 441,277.

To all whom it may concern:

Be it known that I, HERMAN BACHARACH, a citizen of the United States, and a resident of Pittsburgh, in the county of Allegheny and State of Pennsylvania, have made a new and useful Invention in Protecting Hoods or Casings, of which the following is a specification.

The invention relates to protecting hoods or casings, and is designed particularly for use with instruments having recording drums such as gages and the like. Such drums are ordinarily covered by casings provided with windows, so that the record on the drums may be observed without removing the casing. Such casings must, however, be removed from time to time to remove the records and apply blanks. The repeated removal and replacement of the casings under such conditions involves considerable labor and the windows are frequently broken in handling or while the casings are removed, and while resting upon the floor or other support upon which it may have been placed. The present invention is designed to overcome this inconvenience making the work of covering and uncovering the drum practically negligible and entirely eliminating the danger of injury to the windows of the hood either in handling the hood or while such hood is in open position. One embodiment of the invention is illustrated in the accompanying drawings, wherein:—

Figure 1 is a front elevation of a gage provided with the improved hood or casing for the recording drum, the dotted lines showing the hood in open position. Fig. 2 is a side elevation of the device of Fig. 1. Figs. 3 and 4 are enlarged front and side elevation views respectively of the hinge and stop construction at the lower edge of each half of the hood with the hood in closed position. And Fig. 5 is a view corresponding to Fig. 3, but with the hood in open position.

Referring to the drawings, 1 is the casing of a gage float, supported in position upon the wall 2 by means of the bracket 3 provided with the collars 4 and 5. Upon the top of the casing is a base member 6 carrying the recording drum 7 with the recording strip 8 thereon adapted to receive a record from the pen or pencil 9 (Fig. 2) operated from the float or other equivalent

device in the casing 1, such mechanism all being well known and constituting no part of or limitation to the present invention, which relates particularly to the hood construction.

The hood is formed in two halves, 10 and 11 shown in full lines in closed position in Fig. 1, and in open position in dotted lines. These half hood members meet and preferably overlap along the vertical line 12 when in closed position, the drum being visible through the windows 13 and 14 provided with suitable transparent sheets of glass, mica or composition. The half members 10 and 11 are each provided at their lower edges with a pair of hinge lugs 15, 15 fitting on opposite sides of the lug 16 integral with the base 6. A pintle 17 extends through the three lugs.

In order to limit the opening movements of the hood sections, the lugs 16 are provided with the inclined stops 18 which engage the side walls of the hood members and support them in the positions indicated in dotted lines in Fig. 1. The centers of gravity of the hood members, when in this position, lie outside the points of pivotal support, so that when such members reach this position, they are maintained by gravity until it is desired to close the hood. The opening thus provided is sufficient to give the necessary access to the drum for replacement of the record, for adjustment, or for any other purpose. At the same time, the sections may be easily removed entirely by withdrawing the pintles 17.

The embodiment of the invention illustrated and described is inexpensive and simple, but it will be understood that considerable modification is possible without departing from the invention, particularly as to the details of the pivoting or hinge construction and as to the stop means. The stop means are preferably made integral with the hinge lugs on the base, but the stop means might be differently constructed and arranged, the invention comprehending any and all means for limiting the opening movements of the hood sections at the desired points.

What I claim is:—

1. A protecting device for a recording drum, comprising a cylindrical gage casing constituting a base, a pair of hood members each substantially semi-cylindrical in hori-

zontal cross section mounted upon the base and pivoted thereto at their lower outer edges, and meeting along their inner vertical edges, and stop means for limiting the outward swinging movement of the hood members, such stop means being arranged to arrest the outward movement of the hood members when the centers of gravity thereof reach points outside the vertical planes of the pivots, and the two hood members engaging along their vertical inner edges when the centers of gravity thereof reach points inside of the vertical planes of the pivots.

2. A protecting device for a recording drum comprising a base, a pair of hood members mounted upon the base and pro-

vided with hinge members at their lower outer edges, lugs on the base to which said hinge members are pivoted, and stop means on the lugs for limiting the outward swinging movement of the hood members, such stop means being arranged to arrest the outward movement of the hood members when the centers of gravity thereof reach points outside the vertical planes of the pivots, and the two hood members engaging along their vertical inner edges when the centers of gravity thereof reach points inside of the vertical planes of the pivots.

In testimony whereof, I have hereunto subscribed my name this 28th day of Jan., 1921.

HERMAN BACHARACH.
